PROCESS FOR MAKING SEAMLESS PANTIES

George Lacks, Larchmont, N. Y.

Application March 15, 1949, Serial No. 81,493

5 Claims. (Cl. 66—177)

1

My invention relates to panties or to similar bifurcated or two-legged garments, for example, to pantie-girdles.

Objects of my invention are to make a pantie that has no sewed, overlapped or otherwise thickened seams, that is formed by interlocking meshes throughout its extent, that will not cause a garment tightly surrounding the pantie to wrinkle or to show projections, and that will adapt itself to the shape of the wearer's body without any inconvenient pressure along seam lines.

Other objects are to make a pantie that combines high stretchability with strong resilient resistance, this resistance being stronger in those directions in which a higher resistance is desirable in order to support the shape of the wearer's abdomen, and to make a pantie having wales running substantially vertical at its leg, front and side portions and having wales running from one leg to the other at its crotch portion.

Further objects are to make a pantie by a quick and economic method, to knit this pantie by partly circular, partly reciprocating operation of one continuously operated knitting machine, and to use, throughout the knitting operation, one continuous strand or thread.

Still other objects and advantages will appear from the following description of an exemplifying embodiment of my invention, from the appended claims and from the accompanying drawing in which:

Fig. 1 shows a top view of a circle of needles, of a needle ring and of an early stage of the pantie being made according to my invention, other parts of the knitting machine and of the thread being omitted.

Fig. 2 shows a cross-section taken along the line 2—2 in Fig. 1.

Fig. 3 shows a cross-section similar to Fig. 2, but showing the pantie in a more advanced stage of manufacture.

Fig. 4 shows a perspective view of the latter stage of the pantie, the same being shown as it would appear if removed from the machine and stretched.

Fig. 5 shows a cross-section similar to Figs. 2 and 3, but representing a still more advanced stage of the manufacture.

Fig. 6 shows a side view of the pantie in a further stage after the knitting has been completed, the knitted body being removed from the knitting machine and stretched in almost flat condition.

Fig. 7 shows another side view of this latter stage, seen from the right side in Fig. 6.

Fig. 8 shows a front view of the final stage of the pantie.

Fig. 9 shows a bottom view of the pantie shown in Fig. 8.

Wherever the thickness of the knitted mate-

2

rial appears in the figures, it is exaggerated for the sake of clearer representation. Figs. 6 to 9 are represented on a smaller scale than Figs. 1 to 5.

In carrying out my invention, I use a number of circularly arranged needles, some of which are indicated by numerals 3 to 6 and 23 to 26. The number of needles may be larger than shown in the drawing. For example, there may be three hundred and fifty needles arranged at equal intervals. Preferably these needles are incorporated in a knitting machine of well known structure allowing the choice between circular and reciprocating operation.

The needles project upwardly from a ring 7 which is a part of the knitting machine, and are movable in vertical direction. Needles can be idled by throwing the same out in well known manner.

During the first period of the manufacture, all needles are active, and the machine knits circularly over the entire circle of needles. This operation continues until the resulting tubular knitted body 8 forms a leg of desired length. This leg portion begins at the line 9 and ends at the line 11. The latter line has just been knitted in the stage shown in Figs. 1 and 2.

Then the knitting continues reciprocatingly over a part of the circle of needles while the other needles are idle. Finally the latter needles are re-activated and circular knitting is resumed. The knitted body is not disengaged from the temporarily idled needles whereby these needles hold the last meshes knitted on them until these meshes are engaged by the knitting thread when the needles are re-activated.

Preferably, not all temporarily idled needles are thrown out at the same time. For example, the needles of the arc from 3 to 23 are idled

40 after the stage shown in Figs. 1 and 2 has been reached. During a following period of reciprocating operation, further needles from 4 to 5 and from 24 to 25 are successively idled whereby the arc of idled needles is step-wise widened, and

45 a gradually narrowing extension 12 (see Fig. 4) is made which extends from an arc of the leg line 11. Preferably, these needles 4 to 5 and 24 to 25 are idled, one after the other, at intervals comprising more than one reciprocation of

50 the knitting machine whereby more than one mesh spans from one of those needles to the next needle. These intervals are so measured that the free edges 13 of the narrowing body portion 12 have an angular direction of suitable inclination.

55 Any desired uniform or varying angle or inclination can be obtained in this manner.

After the portion 12 has reached the desired length and width, reciprocating knitting continues without further change in the number of active needles. In this manner, a further portion

14 of uniform width is knitted. When the portion 14 has reached a certain length which depends on the desired height of the pantie, half of the knitted body is completed, the knitting having proceeded up to line 15. Fig. 4 represents this stage of the knitted body in a shape into which the knitted product could be unfolded or stretched if the operation would be interrupted at this stage. In fact, the body being knitted remains in the machine where it engages the needles and hangs down from the same about in the manner illustrated by Fig. 3. This figure is a cross-section showing one half of the body which is symmetric to the cut off half, except that the hanging down parts may form irregular folds.

During the reciprocating operation or, at least, during the knitting of portion 14, selvedged edges are made by well known movements of those needles which are at both ends of the active arc, for example, by reciprocating movements of the needles 6 and 26. These selvedged edges are indicated by dotted lines 16.

From the stage shown in Fig. 3, the knitting proceeds in the described manner, but in reverse order, that is, first a portion 17 of uniform width is made which is an identical continuation of the portion 14, then a gradually widening portion 18 identical to the narrowing portion 12 is knitted, and then a leg portion 19 identical to the leg 8, the operation being reciprocating during the knitting of 17 and 18 and being circular during the knitting of 19. While the portion 18 is knitted, the needles from 5 to 4 and from 25 to 24 are stepwise re-activated at intervals corresponding to their prior idling. At the start of the knitting of the second leg portion 19, the needles positioned from 3 to 23 are re-activated. The mesh held by any re-activated needle is engaged by the thread which continues knitting when the needle is activated.

Fig. 5 shows the knitted body at a time when the circular knitting has been resumed and a small zone of the second leg 19 has been knitted. This figure shows a cut off half of the knitted body which is symmetric to the other half, except that the hanging down parts may form irregular folds.

After completion of the leg 19, the knitted body comprises two symmetrically made portions, one of which is represented in Fig. 4. But the entire body can not be stretched as shown in this figure because certain lines of the symmetric portions are connected where meshes positioned on temporarily idled needles have been engaged.

Then the knitted body is taken out of the knitting machine. At this stage, the body may be stretched and folded in the almost flat shape shown in Figs. 6 and 7. The body comprises the legs 8 and 19 and an extension which comprises the tapering portions 12 and 18 and the uniformly wide portion 14—17 bent along the line 15. This extension connects outer arcs of the two legs. Inner arcs of the legs are immediately connected to each other along the line 21.

The tapering portions 12 and 18 are connected along the lines 13 which may be folded inwardly as shown in Figs. 6 and 7. This connection is of still higher stretchability than the other parts of the knitted body, because the meshes establishing the connection are spaced by intervals as has been pointed out before. This facilitates the adaptation of the parts bordering the line 21 to the shape of the wearer's body, these

parts forming a crotch 22 spanning from one leg to the other.

Then each of the two selvedged edges 16 of the portion 14 is connected to that selvedged edge of the portion 17 which belongs to the same side or edge of the extension. In this manner, the extension is transformed into a pocket which, at its lower side, gradually turns into the legs and, at its upper side, is closed along the line 15. This connection is preferably made on a looping machine. The line of looping stitches made by this machine is schematically indicated in Fig. 8 by the zig-zag line 27.

Then the knitted body is cut along the line 15 whereby the pocket is opened along a circularly coherent rim. This rim may be then provided with a hem 28. The final shape obtained in this manner is represented in Figs. 8 and 9. These figures show the pantie spread in a position ready for being slipped on the wearer's body. The crotch 22 comprises adjacent parts of the two legs and may form folds 29. On the wearer's body, the crotch and the other parts of the pantie adapt themselves to the shape of this body, cover the same smoothly and exert a resilient pressure which supports this shape. The wales run substantially in the same directions as the surface shade lines.

The structure of ordinary knitting meshes is well known and is not shown in the drawing. Somewhat larger "dots" or mesh openings appear, when the portions 12 and 18 are stretched, at those spots where, during the knitting, intervals have been made between successively idled and mesh-retaining needles. These "spots" are indicated in Figs. 8 and 9 by the dots of the lines 31. The stretchability of the knitted body is favorably increased in the direction across these lines.

I desire it understood that my invention is not confined to the particular embodiment shown and described, the same being merely illustrative, and that my invention may be carried out in other ways without departing from the spirit of my invention as it is obvious that the particular embodiment shown and described is only one of the many that may be employed to attain the objects of my invention.

Having described the nature of my invention, what I claim and desire to protect by Letters Patent is:

1. A method of making panties or the like two-legged garments, said method comprising making a leg by circularly knitting over a number of needles arranged in a circle, then idling needles along an arc of said circle, continuing knitting reciprocatingly over the remaining needles and thereby making an extension extending from an arc of said leg, then activating said idled needles, continuing knitting circularly and thereby making the other leg, the start of said latter circular operation engaging the meshes positioned on said temporarily idled needles whereby a narrow crotch-connection is made between arcs of said legs, and said extension connects the remaining arcs of said legs over a considerably longer distance, then connecting one half of each edge of said extension to the other half of the said edge and thereby transforming said extension into a pocket having a closed line at that end which is far from said legs, and then cutting through said line.

2. A method of making panties or the like two-legged garments, said method comprising making a leg by circularly knitting over a number of needles arranged in a circle, then idling needles

along an arc of said circle, continuing knitting reciprocatingly over the remaining needles, increasing the arc of idled needles by idling successively further needles at both sides from said first idled needles and thereby making a gradually narrowing extension portion extending from an arc of said leg, then continuing knitting reciprocatingly over the remaining needles and thereby making a further extension portion of uniform width, then activating successively said successively idled needles and thereby making a gradually widening third extension portion, said third portion engaging the meshes positioned on said successively idled needles and thereby connecting said widening portion with said narrowing extension portion, then activating said first mentioned idled needles, continuing knitting circularly and thereby making the other leg, the start of said latter circular operation engaging the meshes positioned on said first mentioned idled needles whereby a narrow crotch-connection is made between arcs of said legs, and said extension connects other arcs of said legs over a considerably longer distance, then connecting one half of each edge of said uniformly wide extension portion to the other half of the same edge and thereby transforming said extension into a pocket having a closed line at that end which is far from said legs, and then cutting through said line.

3. A method of making panties or the like two-legged garments, said method comprising making a leg by circularly knitting over a number of needles arranged in a circle, then idling needles along an arc of said circle, continuing knitting reciprocatingly over the remaining needles, increasing the arc of idled needles by idling successively further needles at both sides from said first idled needles and thereby making a gradually narrowing extension portion extending from an arc of said leg, successive needles being idled at intervals comprising more than one reciprocation of the knitting, then continuing knitting reciprocatingly over the remaining needles and thereby making a further extension portion of uniform width, then activating successively said successively idled needles at intervals corresponding to said first mentioned intervals and thereby making a gradually widening third extension portion, said third portion engaging the meshes positioned on said successively idled needles and thereby connecting said widening portion with said narrowing extension portion, then activating said first mentioned idled needles, continuing knitting circularly and thereby making the other leg, the start of said latter circular operation engaging the meshes positioned on said first mentioned idled needles whereby a narrow crotch-connection is made between arcs of said legs, and said extension connects other arcs of said legs over a considerably longer distance, then connecting one half of each edge of said uniformly wide extension portion to the other half of the same edge and thereby transforming said extension into a pocket having a closed line at that end which is far from said legs, and then cutting through said line.

4. A method of making panties or the like two-legged garments, said method comprising making a leg by circularly knitting over a number of needles arranged in a circle, then idling needles along an arc of said circle, continuing knitting reciprocatingly over the remaining needles, increasing the arc of idled needles by idling successively further needles at both sides from said

first idled needles and thereby making a gradually narrowing extension portion extending from an arc of said leg, then continuing knitting reciprocatingly over the remaining needles and thereby making a further extension portion of uniform width, making selvedged edges during said latter reciprocating operation, then activating successively said successively idled needles and thereby making a gradually widening third extension portion, said third portion engaging the meshes positioned on said successively idled needles and thereby connecting said widening portion with said narrowing extension portion, then activating said first mentioned idled needles, continuing knitting circularly and thereby making the other leg, the start of said latter circular operation engaging the meshes positioned on said first mentioned idled needles whereby a narrow crotch-connection is made between arcs of said legs, and said extension connects other arcs of said legs over a considerably longer distance, then connecting one half of each edge of said uniformly wide extension portion to the other half of the same edge by a looping operation engaging said selvedged edge and thereby transforming said extension into a pocket having a closed line at that end which is far from said legs, and then cutting through said line.

5. A method of making panties or the like two-legged garments, said method comprising making a leg by circularly knitting over a number of needles arranged in a circle, then idling needles along an arc of said circle, continuing knitting reciprocatingly over the remaining needles, increasing the arc of idled needles by idling successively further needles at both sides from said first idled needles and thereby making a gradually narrowing extension portion extending from an arc of said leg, then continuing knitting reciprocatingly over the remaining needles and thereby making a further extension portion of uniform width, then activating successively said successively idled needles and thereby making a gradually widening third extension portion, said third portion engaging the meshes positioned on said successively idled needles and thereby connecting said widening portion with said narrowing extension portion, then activating said first mentioned idled needles, continuing knitting circularly and thereby making the other leg, the start of said latter circular operation engaging the meshes positioned on said first mentioned idled needles whereby a narrow crotch-connection is made between arcs of said legs, and said extension connects other arcs of said legs over a considerably longer distance, all said knitting steps being made on the same knitting machine with one continuous thread, then connecting one half of each edge of said uniformly wide extension portion to the other half of the same edge and thereby transforming said extension into a pocket having a closed line at that end which is far from said legs, and then cutting through said line.

GEORGE LACKS.
